ROTOR FOR TURBO-BLOWERS, CENTRIFUGAL PUMPS AND THE LIKE

Application filed June 20, 1930, Serial No. 462,654, and in Japan November 2, 1929.

This invention relates to improvements in or relating to rotors of turbo-blowers, centrifugal pumps and the like, made up of two or more disks coupled elastically by means of 5 vanes. The object of the invention is to obtain a strong and efficient rotor while reducing the greatest circumferential stress at the inner edge of the cover disk to the value equal or almost equal to that in the main disk at the 10 point situated at the same radial distance as the inner edge near the opening in the cover disk, and the stress in the material of the vanes as small as possible, by making the radial displacements and the stresses at the 15 points of the same radial distances in both disks as nearly equal as possible. And especially by making equal or similar the thicknesses of the main and cover disks of the rotor of a turbo-blower or centrifugal pump, and 20 by fitting on the innermost radial part of the cover disk which has the larger central opening, a proper shrinkage ring or rings to produce such a proper inward pressure that, when the thicknesses are equal, the cover disk 25 carrying half the material of the elastic coupling of the disks as the load due to the centrifugal force, will undergo the same radial displacement as the main disk; and that, when the thicknesses are not equal but ap- 30 proximately so, the cover disk carrying a part of the material of coupling in proportion to the thicknesses of disks will undergo almost the same radial displacement as the main disk.

35 In the accompanying drawings Fig. 1 is a sectional elevation of an example of a six stage turbo-blower fitted with the rotors of our invention. Fig. 2 is a similar sectional elevation of an example of an eight stage 40 turbo-blower of the same capacity as that shown in Fig. 1, but fitted with ordinary rotors. Fig. 3a represents in full lines a half radial section of one practical example of the first stage rotor of our invention with 45 shrinkage rings shown in Fig. 1 with its di-

mensions in millimeters, and showing in chain lines a similar half section of the cover plate of the rotor of ordinary design as shown in Fig. 2, so as to compose a complete rotor when it is fitted to the main disk of the rotor represented in full lines in Figs. 2 and 3a, with the vanes of a properly increased width as shown in Fig. 1. Fig. 3b represents a sectorial part of a rotor as in Fig. 3a, without cover plates, showing the shape and the arrangement of the 50 vanes. Fig. 3c represents in full lines the curves of the radial and circumferential stresses in kilogrammes per square centimeter in the main and the cover disks of the rotor of our invention shown in Figs. 1 and 3a 55 against the abscissae of the radial distance of the point in rotor, when it revolves at a speed of 5850 revolutions per minute; and there is also shown in chain lines the similar 60 curves of the stresses in the rotor of ordinary design represented also in Figs. 2 and 3a composed of a cover plate represented in chain 65 lines joined to the main disk with vanes of a greater width as shown in Fig. 3a when it revolves at a speed of 4840 revolutions per 70 minute. Fig. 4 represents a radial section similar to Fig. 3a partly broken away of the 75 rotor of our invention. Fig. 5 represents a section similar to Fig. 3b, showing only a sectorial part, of the rotor represented in Fig. 4, with cover plate removed to show the shape 80 and the number of the vanes. Fig. 6 represents an axial view of an elementary part of the main disk bounded by two radial planes making a small angle of $\delta\theta$ passing through 85 the axis of rotation of the rotor, and two concentric cylindrical surfaces with their axes coinciding with the axis of rotation of the rotor and their radii differing by a small amount δr . Fig. 7 is a section on line OX of 90 the same elementary part as shown in Fig. 6. Fig. 8 is a diametrical section similar to Figs. 3a and 4 of a conventional form of rotor consisting of one main disk and two cover disks each having a relatively large central

opening for the admission of gas and showing the application of the invention thereto. Similar characters of references indicate corresponding parts throughout the figures 5 and referring now to the same:

A in Fig. 1 and A' in Fig. 2 are the rotors of turbo-blowers mounted on the shafts H and enclosed in the casings M with partition walls P defining a plurality of separate 10 chambers UU, in each of which is situated a rotor A or A', a guide vane ring B, and a return passage C. In Figs. 1 and 2, when the shaft H is rotated by a suitable prime mover, 15 which is not shown in the figures coupled to the shafts at the end H, air or gas will be sucked in by the rotational action of the rotors from the inlet opening S of the casing M, and passes into the rotor from the suction opening E of the first rotor A or A', and is de- 20

coupling, or vanes in case of the rotor of a turbo-blower, be proportional to the difference of radial displacements of the main and the cover disks, e_1 and e_2 ; whilst the factor of proportionality G, is a certain function of 70 the radial distance r , to be determined by the geometrical configuration and the elastic properties of the coupling or vanes. The force may, therefore, be expressed as follows:

$F_1 = (e_2 - e_1) G(r)$, force exerted by the 75 cover disk on the main disk in direction of increasing radius, and

$F_2 = (e_1 - e_2) G(r)$, force exerted by the main disk on the cover disk in direction of increasing radius, each per unit area on the 80 normal surfaces to the axis of revolution of the disks. Considering the equilibrium of an elementary part of the main disk as shown in Figs. 6 and 7, we have the following equation of equilibrium of forces, 85

$$f\theta y_1 \delta r \delta \theta + f r_1 y_1 r \delta \theta - (f r_1 + \delta f r_1) (r + \delta r) \delta \theta (y_1 + \delta y_1) - G(e_2 - e_1) r \delta \theta \delta r = \mu \omega^2 r \left\{ y_1 r \delta \theta \delta r + n z \frac{t}{\sin \gamma} \delta r (1 - \xi) \frac{\delta \theta}{2\pi} \right\}$$

25 livered at its outer periphery p under a higher pressure and velocity, and then passes into the guide vanes B, where the velocity of the air or gas is reduced and the pressure is further increased. Then the air or gas enters 30 into the return passage C of the chamber U, and is sucked through the eye E' into the next rotor. The air or gas is thus compressed in stages through the several rotors and is delivered finally, through the last annular passage 35 Q of the last guide vane ring, to the delivery opening D of the casing M.

In considering the equilibrium of the two rotating disks, such as in the case of the rotors of turbo-blowers, the assumptions 40 adopted ordinarily are (1) the stress distribution in the disk is considered as uniform in the direction parallel to the axis of rotation, (2) the width of the disk in the direction parallel to the axis of rotation changes 45 very gradually, and (3) points situated at equal radial distances at rest will remain also at equal radial distances from the axis of rotation when running. To these assumptions ordinarily adopted we add further- 50 more the following which are necessary for the new method of analysis first introduced by the inventors: (4) The elastic force caused by the coupling of the two disks is assumed to be distributed uniformly on the 55 points situated at the same radial distances from the center of rotation of the rotor, and (5) the direction of the forces caused exerted on the discs by the coupling are assumed to be radial.

60 In Figs. 4 and 5, the main disk is designated by 1 and the cover by 2. a is the outermost radius which is the same for both disks; b is the innermost radius of the cover disk, disregarding the packing ring of the rotor. As- 65 sume that the force caused by the elastic

where

$f\theta$, and $f r_1$, principal circumferential and radial stresses in the main disk,

$f\theta_2$ and $f r_2$, principal circumferential and radial stresses in the cover disk, 95

y_1 and y_2 , axial thicknesses of the main and cover disks,

e_1 and e_2 , radial displacements of the points in the main and the cover disks,

r , radial distance of the point in the disks, 100 as shown in Figs. 4 and 5,

θ , angle measured in the direction of rotation,

$G(r)$, radial outward force exerted by the cover disk on the unit area of the normal surface of the main disk through vanes, 105 when $(e_2 - e_1)$ is unity,

μ , density of material of disks and vanes, that is, specific gravity divided by g ,

ω , angular velocity of rotation of disks,

n , number of vanes, 110

z , width of vane, as shown in Fig. 4,

t , thickness of vane, as shown in Fig. 5,

γ , angle of vane, as shown in Fig. 5,

ξ , function of r , its value being a fraction between zero and unity, and the part ξz of vane being assumed to have the effect of its centrifugal force on the cover disk, whilst the part $(1 - \xi)z$ on the main disk as shown in Fig. 4. 115

Putting in the equation of equilibrium now 120 obtained the stresses given by the following equations

$$f\theta = \frac{E}{1 - \nu^2} \left\{ \nu \frac{de}{dr} + \frac{e}{r} \right\},$$

and

$$fr = \frac{E}{1 - \nu^2} \left\{ \frac{de}{dr} + \nu \frac{e}{r} \right\}$$

where E = Young's modulus of elasticity, 130
 ν = Poisson's ratio,

we have for the equation of the displacement of the main disk

$$5 \frac{d^2e_1}{dr^2} + \left(\frac{1}{y_1} \frac{dy_1}{dr} + \frac{1}{r} \right) \frac{de_1}{dr} + \left(\frac{\nu}{r} \frac{1}{y_1} \frac{dy_1}{dr} - \frac{1}{r^2} \right) e_1 + \frac{1-\nu^2}{E} \frac{G}{y_1} (e_2 - e_1) + \frac{1-\nu^2}{E} A r + \frac{1-\nu^2}{E} A \frac{ntz}{2\pi \sin \gamma} \frac{1-\zeta}{y_1} = 0 \quad (1), \quad 70$$

where $A = \mu \omega^2$. For the cover disk, we have a similar equation:

$$10 \frac{d^2e_2}{dr^2} + \left(\frac{1}{y_2} \frac{dy_2}{dr} + \frac{1}{r} \right) \frac{de_2}{dr} + \left(\frac{\nu}{r} \frac{1}{y_2} \frac{dy_2}{dr} - \frac{1}{r^2} \right) e_2 - \frac{1-\nu^2}{E} \frac{G}{y_2} (e_2 - e_1) + \frac{1-\nu^2}{E} A r + \frac{1-\nu^2}{E} A \frac{ntz}{2\pi \sin \gamma} \frac{\zeta}{y_2} = 0 \quad (2)$$

15 If we suppose two virtual disks, one made up of the cover disk of the complete rotor and a part ζz of the vanes as shown in Fig. 4, and the other of the main disk and the remaining part $(1-\zeta)z$ of the vanes; the equations of 20 the displacements in these separate disks will be those obtained by putting in Equations (1) and (2), G equal to zero, that is,

$$25 \frac{d^2e_1}{dr^2} + \left\{ \frac{1}{y_1} \frac{dy_1}{dr} + \frac{1}{r} \right\} \frac{de_1}{dr} + \left\{ \frac{\nu}{r} \frac{1}{y_1} \frac{dy_1}{dr} - \frac{1}{r^2} \right\} e_1 + \frac{1-\nu^2}{E} A r + \frac{1-\nu^2}{E} A Z \frac{(1-\zeta)}{y_1} = 0 \quad (1)'$$

$$30 \frac{d^2e_2}{dr^2} + \left\{ \frac{1}{y_2} \frac{dy_2}{dr} + \frac{1}{r} \right\} \frac{de_2}{dr} + \left\{ \frac{\nu}{r} \frac{1}{y_2} \frac{dy_2}{dr} - \frac{1}{r^2} \right\} e_2 + \frac{1-\nu^2}{E} A r + \frac{1-\nu^2}{E} A Z \frac{\zeta}{y_2} = 0 \quad (2)'$$

where $Z = ntz/2\pi \sin \gamma$.

35 When the thicknesses y_1 and y_2 of the two disks are of a constant ratio k , that is $y_1 = y_2 k$, for every radial distance, the Equations (1)' and (2)' will be identical if $(1-\zeta)/y_1 = \zeta/y_2$, or $\zeta = 1/(k+1)$. In such a mode of dividing up the vanes, all the axial dimensions of the

disks will be identical all over the disks. When the thicknesses are not similar, there

will be always only one method of dividing up the vanes, so as to make the displacements

of the virtual disks equal. In such a case, we must have

$$e_1 = e_2 = e, \frac{de_1}{dr} = \frac{de_2}{dr} = \frac{de}{dr}, \frac{d^2e_1}{dr^2} = \frac{d^2e_2}{dr^2} = \frac{d^2e}{dr^2}, \quad 75$$

and

$$fr_1 = fr_2 = fr. \quad 85$$

Utilizing these, we have from (1)' and (2)'

$$\frac{de}{dr} + \nu \frac{e}{r} = S\zeta - T = \frac{1-\nu^2}{E} fr \quad (3) \quad 90$$

where

$$S = \frac{1-\nu}{E} AZ \left(\frac{1}{y_1} + \frac{1}{y_2} \right) / \left(\frac{1}{y_1} \frac{dy_1}{dr} - \frac{1}{y_2} \frac{dy_2}{dr} \right) \quad (4)$$

$$T = \frac{1-\nu^2}{E} AZ \frac{1}{y_1} / \left(\frac{1}{y_1} \frac{dy_1}{dr} - \frac{1}{y_2} \frac{dy_2}{dr} \right) \quad (5) \quad 95$$

The Equation (3) will be integrated easily, and will have the form

$$e = e(r_1 \alpha) = \frac{1}{r^\nu} \int r^\nu (S\zeta - T) dr + \frac{\alpha}{r^\nu} \quad (6) \quad 100$$

where α is a constant of integration. Putting this in Equations (1)' or (2)', and of course making $G=0$, we have

105

$$d^2\xi \frac{d^2\xi}{dr^2} + \left\{ \frac{S^1 + p(r)}{S} + \frac{\nu+2}{r} \right\} \frac{d\xi}{dr} + \left\{ \frac{p'(r)}{S} + \frac{(\nu+2)p(r)}{rS} - \frac{1-\nu^2}{r^2} \right\} \xi + \left\{ \frac{q'(r)}{S} + \frac{(\nu+2)q(r)}{rS} + \frac{(1-\nu^2)}{r^2 S} T \right\} = 0 \quad (7)$$

45 two virtual disks are in a constant ratio of k , with their equations of displacements identical. So we have their displacements e_1 and e_2 , that is, the solutions of the equations, 50 equal; if we have the same boundary conditions. Generally we have the same outermost radii for the both disks in rotors of ordinary construction, but the innermost radii of the holes are different, being generally larger in the cover than in the main disk.

55 The boundary conditions in the innermost edges of the both disks are, therefore, different. If we put on a proper shrinkage ring or rings R at the innermost edge of the cover disk, giving a proper inward pressure, the boundary condition at the inner edge of the cover may be made equal to that at the point in the main disk situated at the equal radial distance as the innermost edge of the cover, 60 and the displacements of the both virtual

where

$$p(r) = \frac{dS}{dr} + \frac{S-T}{y_1} \frac{dy_1}{dr} + \frac{T}{y_2} \frac{dy_2}{dr} + \frac{(1+\nu)}{r} S \quad (8)$$

$$q(r) = -\frac{dt}{dr} - \frac{T}{y_2} \frac{dy_2}{dr} - \frac{(1-\nu)T}{r} + \frac{1-\nu^2}{E} Ar - \frac{1-\nu^2}{r^{\nu+2}} \alpha \quad (9) \quad 115$$

$$S' = \frac{dS}{dr}, p'(r) = \frac{dp}{dr}, q'(r) = \frac{dq}{dr}. \quad 120$$

Solving Equation (7) we can determine the method of dividing and the vanes so as to make $e_1 = e_2$. After we have thus known the function ξ giving the method of separation of the whole disk into two virtual disks, we can easily calculate the necessary shrinkage ring or rings to be fitted on the innermost edge of the cover disk so as to make the dis-

130

placements e_1, e_2 and the stresses in the both virtual disks equal.

The complete actual rotor made up of the virtual disks coupled elastically by the vanes is, however, different from those virtual ones. The actual rotor, being two or more rotating disks elastically coupled, will assume in revolution a position of the minimum strain energy under the condition of stable equilibrium. The function ζ will be such that satisfies this condition, and it is not easy to find the actual form of the function ζ , excepting in some special cases. There will not be, however, much error in assuming ζ as given by $\zeta = 1/(k+1)$ in case of similar disks, and that given by Equation (7) in case of dissimilar disks, if the material of the vanes is not very much in comparison with that of the both disks in all. And further when the disks have similar thicknesses, the error is very small; and, moreover, when they are of the same thickness, but have only a different innermost diameter of the holes, k will be unity and ζ will be $1/2$, it is not difficult to prove that the position of the stable equilibrium giving the minimum strain energy of the complete rotor will be that due to the partition of the vanes by ζ equal to $1/2$, or just the same as in the case of virtual disks separated by the function $\zeta = 1/(k+1) = 1/2$.

It will be easily supposed that, even in the case of dissimilar disks, the difference of the radial displacement of both disks with the proper shrinkage ring or rings as calculated for the two virtually separated disks according to the method invented by the inventors, are very small compared with that of the

$$\frac{d^2 e_2}{dr^2} + \left(\frac{1}{y_1} \frac{dy_1}{dr} + \frac{1}{r} \right) \frac{de_2}{dr} + \left(\frac{\nu}{r} \frac{1}{y_1} \frac{dy_1}{dr} - \frac{1}{r^2} \right) e_2 - k \frac{1-\nu^2}{E} \frac{G}{y_1} (e_2 - e_1) + \frac{1-\nu}{E} Ar + k \frac{1-\nu^2}{E} AZ \frac{\zeta}{y} = 0 \quad (2)''$$

disks without shrinkage. In Figs. 3a and 3b, part sections of an ordinary rotor A' are represented, consisting of dissimilar disks 1, indicated in full lines, and 2', indicated in chain lines, and Fig. 3c gives in chain lines the stresses in the two disks when running at a speed of 4840 revolutions per minute, calculated by the ordinary method, assuming the vanes as the load on the main disk and the cover without vanes; that is, $\zeta = 0$ and $G = 0$.

The curves represented in full lines in Fig. 3c are the stresses for the virtual disks obtained by dividing up, so that $\zeta = 3/(4+3)$, the rotor A represented in Fig. 1 and Fig. 3a in full lines, and with the cover similar to and $3/4$ as thick as the main disk having shrinkage rings R represented in Fig. 3a according to this invention when they are run at a speed higher than 5580 revolutions per minute. As has been explained previously, the stresses and the displacements in the disks of an actual rotor will not be much different from those calculated and represented in full lines in Fig. 3c for the two vir-

tual disks. It will be noticed that the circumferential stress $f\theta_2$ in the cover disk of the ordinary rotor seems to be very great at its innermost edge, whilst the radial stress fr_2 is nil, and very small all over in the cover. The part of the cover, therefore, near the riveting holes for fastening the vanes will be liable to be subjected to a heavy stress of about three times the large circumferential stress $f\theta_2$ in the cover. By aid of our invention of strengthening the cover with a proper shrinkage ring or rings R, the circumferential stress $f\theta_2$ in the cover will be reduced equal or almost equal to that in the main disk as shown in Fig. 3c even at a higher speed, and moreover the radial stress fr_2 in the cover will be increased equal or almost equal to that in the main disk fr_1 . The heavy stress, therefore, in the neighbourhood of the holes for riveting vanes will be greatly reduced. Thus greater safety and reliability of the rotor in every respect is attained even at a higher speed.

With this increased speed of revolutions from 4840 to 5580, the number of the stages of the turbo-blower in consideration is reduced from eight to six as shown by comparison of Figs. 1 and 2, which was simply effected by modifying the cover only, but not the main disk. With the proper modifications of both the cover and the main disks suitable to carry the new invention into practice, a further reduction in the number of the stages will be effected.

When the disks are similar in thickness the Equation (2) will be reduced to

The solutions of Equations (1) and (2)'' will be

$$e_1 = \phi(r) - \psi(\zeta, r) \quad (10)$$

$$e_2 = \phi(r) + k\psi(\zeta, r) \quad (11)$$

where ϕ is a certain function of radial distance r , and ψ of ζ and r , both of which will depend on the forms of the Equations (1) and (2)'. From these equations of displacements, we can derive the equations of the principal radial and circumferential stresses, and they are

$$fr_1 = \frac{E}{1-\nu^2} \left\{ \Phi_r(r) - \Psi_r(\zeta, r) \right\} \quad (12)$$

$$f\theta_1 = \frac{E}{1-\nu^2} \left\{ \Phi_\theta(r) - \Psi_\theta(\zeta, r) \right\} \quad (13)$$

$$fr_2 = \frac{E}{1-\nu^2} \left\{ \Phi_r(r) + k\Psi_r(\zeta, r) \right\} \quad (14)$$

$$f\theta_2 = \frac{E}{1-\nu^2} \left\{ \Phi_\theta(r) + k\Psi_\theta(\zeta, r) \right\} \quad (15)$$

where

$$\Phi(r) = \frac{d\phi}{dr} + \nu \frac{\phi}{r}, \quad \psi_r(r) = \frac{\delta\psi}{\delta r} + \nu \frac{\psi}{r}$$

$$\Phi_\theta(r) = \nu \frac{d\phi}{dr} + \frac{\phi}{r}, \quad \psi_\phi(r) = \nu \frac{\delta\psi}{\delta r} + \frac{\psi}{r}$$

From these equations of displacements and stresses, it will not be difficult to find the form of the function ζ satisfying the condition of the minimum strain energy; and it is found that in the case where the disks are similar in thickness, the form of ζ previously determined for the separation into two virtual disks having equal displacements is not much different from that giving the minimum strain energy in the complete actual disk. And further it is deduced that when the disks are equal in thickness, the constant value of $\zeta = \frac{1}{2}$ will be that giving to both the virtual and actual disks equal displacements and stresses, giving practically the least stress in the material of the elastic coupling, that is vanes, of the disks.

From the foregoing it is obvious that the invention may be as well applied to a rotor of the type illustrated in Fig. 8 consisting of three discs, the two cover discs of which are provided with central inlet openings. In applying the foregoing calculation to the rotor to find proper shrinkage rings to be fitted to the cover discs, assume that half the thickness of the main disc belongs to a cover disc when the passages on both sides of the main discs are of equal width, as shown in Fig. 8.

We claim.

1. A rotor for turbo-blowers, centrifugal pumps and the like including vanes, discs coupled together elastically by said vanes, one of said discs having an inner opening, and a shrinkage ring fitted on the innermost radial part of said disc and rendering the displacements and stresses in both discs substantially equal.

2. A rotor for turbo-blowers, centrifugal pumps and the like including vanes, a central disc and two outer discs, said outer discs having inner openings, the central disc being coupled elastically with each of the outer discs by said vanes, and a shrinkage ring fitted on the innermost radial part of each of said outer discs and rendering the displacements and stresses in the three discs substantially equal.

In testimony whereof they affix their signatures.
